J. M. Thomas ATTORNEY

UNITED STATES PATENT OFFICE.

CHRISTIAN GERBER, OF MORGAN, UTAH.

SHIP-BOW SHIELD AND SHOCK-ABSORBER.

1,130,809.

Specification of Letters Patent.

Patented Mar. 9, 1915.

Application filed October 19, 1914. Serial No. 867,552.

To all whom it may concern:

Be it known that I, CHRISTIAN GERBER, a citizen of the United States, residing at Morgan, in the county of Morgan and State of Utah, have invented certain new and useful Improvements in Ship-Bow Shields and Shock-Absorbers, of which the following is a specification.

My invention relates to ship-bow shields and shock absorbers and has for its object to provide a shield for the bow of a ship which will act as a shock absorber and deaden the force of the contact when the ship on which it is placed strikes another vessel or some other obstacle. These objects I accomplish with the device illustrated in the accompanying drawings in which similar letters and numerals of reference indicate like parts throughout the several figures, and as described in the specification forming a part of this application and pointed out in the appended claims.

In the drawings in which I have shown a substantial embodiment of my invention, Figure 1 is a side elevation of the front portion of a ship equipped with one of my shields. Fig. 2 is a vertical longitudinal section through the same. Fig. 3 is a plan view of the same portion of the ship with the deck removed showing the device in place thereon. Fig. 4 is a horizontal section on line *x-x* of Fig. 2. Fig. 5 is a horizontal section on line *z-z* of Fig. 2.

When a ship strikes a vessel, iceberg or other obstacle with its prow or bow end, damages are frequently the result even when the ship is not moving with any great speed; and when the speed is great serious loss may occur.

It is the purpose of this invention to provide a shield which is secured to and covers a portion of the bow end of a ship that will deaden the impact and protect that portion of the vessel.

In the drawings filed herewith the bow of the vessel is shown at A and the shield complete as B. Said shield is constructed with an outer covering 1 shaped to conform to the bow of the vessel and normally spaced therefrom. A vertical beam 2 is secured within the apex of said shield or covering made of strong material and provided with recesses 3 which are cut or mortised in the open edge thereof. Horizontally placed buffer bars are carried in the front portion of the vessel extending forwardly therefrom

and each having a pivot ring or plate 4 thereon. Said shield B is fastened in place on the vessel by said rings or plates 4 being inserted within said recesses 3 and pivot bolts 5 secured transversely through the sides 1 of said shield and passed through holes in said pivot plates 4. Said buffer bars are slidably carried in pipes 6 which are secured in place in the frame work of the vessel. Secured within the hold of the vessel and to the heavy frame work thereof are cross braces 7, 8, and 9. On the upper of said buffer bars, shown at 12, is carried a spiral spring 13, one end of which bears against a collar 14 that is rigidly secured on said buffer bar 12, and the other end bears against the cross brace 8. This construction and arrangement allows said buffer bar 12 to be moved longitudinally inward against the compression of said spring 13 which spring normally holds said collar 14 against the inner side of the bow of the vessel. The next lower of said buffer bars 15 is yieldingly held extended and allowed limited longitudinal movement within its pipe 6 by a similar spring 16. The next lower of said buffer bars 17 has a cross-head 18 firmly secured on the free end thereof, and a spring 10 is carried on said bar that tends to hold it extended. On the end portions of said cross-head 18 are secured two parallel horizontally disposed bars 19, with their free ends slidable through openings in the cross brace 9. On each of said bars 19 is carried a spiral spring 20 which is compressed when said buffer bar 17 and cross-head 18 are moved horizontally inward. On the next lower of said buffer bars 21 I preferably carry two spiral springs 22 and 23 each held between a collar 24 and 25 respectively and the cross braces 8 and 9 adjacent.

In the lower hold of the vessel I provide two parallel buffer bars 26 with pivot plates 3 similar to those on the front end of the other buffer bars. On each of said bars 26 is carried a spiral spring 27 which normally holds said buffer bars in their extended position but will allow them to be forced horizontally inward to a limited extent.

Should a vessel upon which my device is fitted strike an object on the upper portion of the shield, the upper buffer bar would be moved longitudinally inward, and the spring 13 would be compressed. The other buffer bars would be in their order down-

ward each moved less than the one above while the springs thereon would be compressed correspondingly. Should the contact be lower and more vertically central on the shield all of said springs would be compressed in proportion to the movement of the shield toward the prow, the strength of the springs determining the relative amount the impact was deadened, the momentum lessened and the final blow lightened.

Having thus described my invention I desire to secure by Letters Patent and claim:—

1. In a shield and shock absorber for ship collisions, a V-shaped shield spaced from the bow of the ship; buffer bars slidably carried in the bow of the ship and to which said shield is pivoted; and spiral springs carried on said buffer bars to normally maintain the space between said shield and the bow of the ship.

2. In a ship-bow shield and shock absorber the combination of horizontally disposed buffer bars slidably carried in the prow of the ship and extended in front thereof; a V-shaped shield pivoted on said buffer bars and spaced from and around the prow of the ship; and spiral springs carried on said buffer bars and within the prow to normally hold said bars extended beyond the prow.

3. In a shock absorber for ships, a ship having a narrowed prow; buffer bars horizontally disposed in said prow; pipes within which said buffer bars are slidably carried; spiral springs carried on said bars to hold them yieldingly extended beyond said prow; and a V-shaped shield pivoted on said buffer bars and normally spaced from said prow.

Copies of this patent may be obtained for five cents each, by addressing the "Commissioner of Patents,
Washington, D. C."

4. In a shock absorber for ships the combination of a ship having a prow narrowed as a cut-water; a buffer bar horizontally disposed and slidably carried in said prow with a portion extended; a spiral spring carried on said buffer bar to hold it yieldingly extended; other buffer bars vertically below said bar and similarly held extended; and a shield pivoted on the extended ends of said bars and shaped to conform to the contour of said prow and normally spaced therefrom.

5. In a shock absorber for ships the combination of a ship having a prow narrowed as a cut-water; a buffer bar horizontally disposed and slidably carried in said prow with a portion extended in front of the prow; a perforated pivot plate on the extended end; a spiral spring carried on said bar to yieldingly hold it extended; another bar vertically below the first mentioned bar; springs carried thereon to hold it normally extended; another buffer bar vertically below the last mentioned bar; a cross-head on the rear end thereof; parallel bars horizontally extended from the rear side of said cross-head; springs carried on said bars to normally hold said buffer bar extended; two parallel spaced apart buffer bars below said last mentioned bar with portions of each forwardly extended; pivot plates on each; and a V-shaped shield pivoted on the extended ends of said bars spaced from said prow.

In testimony whereof I have affixed my signature in presence of two witnesses.

CHRISTIAN GERBER.
